UNITED STATES PATENT OFFICE.

JACOB P. HOLTZHOUSER, OF NEW BRITAIN, CONNECTICUT, ASSIGNOR TO THE STANLEY WORKS, OF NEW BRITAIN, CONNECTICUT, A CORPORATION OF CONNECTICUT.

MOP.

1,247,959.

Specification of Letters Patent. Patented Nov. 27, 1917.

Application filed September 22, 1914. Serial No. 863,008.

To all whom it may concern:

Be it known that I, JACOB P. HOLTZHOUSER, a citizen of the United States, and a resident of New Britain, in the county of 5 Hartford and State of Connecticut, have invented certain new and useful Improvements in Mops, of which the following is a specification.

The object of this invention is to provide 10 an article of the character described having features of a novelty and advantage. The invention relates particularly to the socket connection between the handle and the mop frame.

15 In the drawings—

Figure 1 is a side view of an embodiment of my invention.

Fig. 2 is a bottom view.

Fig. 3 is a sectional view on the line 3 3 20 of Fig. 1.

Fig. 4 is a detail perspective view of the holder plate.

Referring to the drawings, *a* denotes the 25 mop frame, *b* the handle, *c* the connector to which the handle is secured and which is itself attached to the mop frame, this invention being concerned with the method of attachment.

Secured to the mop frame is the holder 30 plate 2 which has two spaced slots 3, the metal between these slots being upset on one side of the plate as indicated at 4, and the metal at the outside of the slots being upset on the other side of the plate as indicated at 5, forming what is in effect a transverse socket formed as to its central portion by upsetting the metal to one side of the plate, and as to its end portions by upsetting the metal at the opposite side of 35 the plate. The connector *c* has arms 6 which fit into the slots 3 in the holder plate 2, and these arms are apertured to receive the pin 7, which fits in the socket in the holder plate passing through the apertures 40 in the arms 6 and connecting the connector *c* to the holder plate. As seen at 8 in Figs. 1 and 3 the pin 7 is connected with the arms 6 to move with them and as the pin has a rather tight bearing in the socket 45 there is thus provided a frictional grip which holds the handle in any desired position of adjustment with respect to the mop frame. The front edges of the arms 6 are

notched as at 9 to allow of sufficient movement of the handle with respect to the frame 55 and constitute a stop to limit the movement of the handle. The rear edges 10 of the arms 6 also form a stop to limit the movement of the handle in the other direction.

By this invention there is provided an 60 extremely simple method of connecting the handle with the mop and providing for an efficient frictional adjustment of the handle with respect to the frame.

I claim as my invention:—

1. In the device of the character described the combination with the mop frame and the handle, of a holder plate secured to the mop frame, a connector to receive the handle, a transverse socket in said holder plate, a pin rotatable in but frictionally gripped by said socket, and means for securing said connector to said pin to cause the pin to move with the connector. 65

2. In the device of the character described the combination with the frame and the handle, of a holder plate secured to the frame, and provided with spaced slots, a socket formed transversely of said holder plate by upsetting the metal between and 70 outside of said slots, on opposite sides of said plate, a connector provided with arms extending through said slots, and a pin fitting in and frictionally gripped by said socket, and passing through and connected 75 to said arms for movement therewith.

3. In a device of the character described, the combination with a mop frame and the handle, of a holder plate secured to the mop frame, and provided with spaced 80 slots, an offset formed in the metal and at one side of said holder plate between said slots, offsets formed in the metal of said holder plate outside of said slots and at the opposite side thereof from said first mentioned offset, the opposed offsets forming a 85 socket extending transversely of said holder plate, a connector provided with arms extending through said slots and a pin fitting in and frictionally held by said socket and 90 passing through and connected to said arms for movement therewith. 95

JACOB P. HOLTZHOUSER.
